SAFETY APPARATUS

Leo L. Weaver, Cranford, N. J., assignor to
 Western Electric Company, Incorporated, New
 York, N. Y., a corporation of New York

Application May 7, 1941, Serial No. 392,332

8 Claims. (Cl. 169—4)

This invention relates to safety apparatus, and more particularly to apparatus for protection against explosively dangerous vapors.

There are innumerable instances in industry where it is necessary to store in temporary or more or less permanent fashion materials which will produce or give off inflammably explosive gases or vapors, especially if abnormal conditions become accidentally created in their immediate environment. Thus, for example, a great variety of mixtures comprising, alone or with other ingredients, a solid such as cellulose acetate softened or dissolved in an inflammable volatile liquid such as acetone, are used in many ways in various arts. In particular, in the art of manufacturing insulated electrical wire, a thickish solution, dispersion or paste of cellulose acetate in acetone with other ingredients is used to coat wire, either bare or having a sheath of insulation thereon to which the cellulose acetate-acetone mixture is applied.

Such mixtures are ordinarily made up and held in some kind of storage tank or receptacle. The mixture may be made up in or supplied to the tank in batches intermittently, as it is used up; or, in some cases, it may be made up continuously at the rate at which it is being used. In either case it is generally preferable to have a substantial pool of the mixture to draw from in order to ensure constancy of protection of ingredients in the mixture, and this pool will be kept in a storage or supply tank or other container. Under normal atmospheric conditions, particularly of temperature, the evolution of vapors from the material in the tank will be insufficient to create any hazard not to be controlled by ordinary means. However, if abnormal conditions arise, e. g. an abrupt and considerable rise in temperature such as might be occasioned by a fire in the building or by the rupture of an adjacent steam line or otherwise, there may occur a relatively enormous evolution of vapor, even enough to burst the tank and to liberate the vapors into the outer air. Being easily inflammable and also capable of making violently explosive mixtures with air, such circumstances are obviously hazardous.

An object of the present invention is to provide means whereby such hazards may be greatly diminished and even substantially prevented, the means being set in operation by the circumstances which tend to create the hazard.

With the above and other objects in view the invention may be embodied, in connection with a receptacle to hold material tending to produce

dangerous vapors and having a normally closed explosion relief aperture therein, in means to open the relief aperture and simultaneously to smother and dilute vapors issuing therefrom with a non-inflammable explosion preventing gas, the said means being actuatable by a device positioned within the receptacle and set in action by the occurrence therein of an abnormal condition.

10 Other objects and features of the invention will appear from the following detailed description of one embodiment thereof taken in connection with the accompanying drawing in which the same reference numerals are applied to identical parts in the several figures, and in which

Fig. 1 is a diagrammatic view in side elevation of an apparatus constructed in accordance with the invention;

Fig. 2 is a portion of Fig. 1 altered to show a modified form;

Fig. 3 is another portion of Fig. 1 similarly altered for the same form; and

Fig. 4 is a view similar to Fig. 2 of another modification.

25 In the embodiment of the invention shown in Fig. 1, a tank 20 is to contain a supply of some mixture 21, such as a liquid or pasty compound containing a volatile, inflammable liquid as one of its ingredients, e. g. acetone, so that the material 21 tends to evolve gases or vapors inflammable and capable of forming explosive mixtures with air. Access may be had to the tank interior to supply or remove material through a suitable aperture in the top, as at 22, tightly closed ordinarily, as by the bolted lid 23. There is another aperture in the top at 24 with an upstanding collar 25 around it and formed at the top with an everted flange 26. A flat ring 27 of internal diameter somewhat larger than that of the collar 25 is secured upon the upper face of the flange 26. A thin, flat, impervious sheet 28 of some suitable material, e. g. aluminum, tin, or other metal, is clamped across the aperture 24 between the flange 26 and the ring 27 so as to close and seal the aperture completely and tightly. Purpose of the sheet or diaphragm 28 is to rupture and afford relief at once should any abnormal increase of pressure arise within the tank, e. g. because of an accidental explosion therein.

30 A plurality (here four) of spacing members 29, each a vertically bored cylinder as shown here, stands on the ring 27 and supports a ring 30 similar in shape to the ring 27, but preferably of slightly smaller internal diameter. On the ring 30 rests a flat, horizontal sheet or diaphragm

31 covering and sealing completely and tightly the aperture of the ring. The diaphragm 31 is a sheet of impervious material, preferably a piece of relatively loosely woven textile fabric such as cheesecloth which has been impregnated and filled with thermosetting plastic such as one of the phenol-formaldehyde resins, or otherwise constructed to be stiff and unyielding up to a certain point under pressure and then to shatter when it yields. An everted flange 32, on the bottom end of a vertical, trumpet-shaped gas delivery member 33, is supported on the diaphragm 31, either directly, or as shown, with a sealing washer 34, of some suitable material such as ordinary rubber impregnated cloth packing.

A gas delivery nozzle 35 in the top of the trumpet 33 is connected by suitable piping to the delivery valve 36 of a compressed gas tank 37 filled with some gas under pressure, e. g. carbon dioxide, nitrogen or the like, which is non-inflammable and tends to prevent or smother fire. The valve 36 is actuatable to open by a lever 38 operable by suitable means such as the weight 39 attached to the lever. The lever is normally held in the valve closing position by a cord or wire rope 40 secured to one horizontal arm 42 of a three-armed lever generally indicated at 41. The weight 39 and cord 40 normally tend to turn the lever 41 clockwise to allow the weight to drop. This is prevented by a detent 45 caught against the upper end of a vertically upstanding arm 43 of the lever 41. The third arm 44 of the lever 41 is formed as a counterpoise weight tending to turn the lever 41 counterclockwise but insufficient to overcome the effect of the weight 39.

The detent 45 is formed on the outer end of one arm of a lever 46 urged clockwise by a spring 48 and held against clockwise motion either by the arm 43 of the lever 41 or by a fixed stop member 49. The lever 46 may be actuated to turn counterclockwise by a push rod 50 acting on the arm 47 of the lever.

The push rod 50 is secured to one end of a corrugated metal bellows 51 into the other end of which an actuating tube 52 is secured to communicate with the otherwise imperforated walled interior of the bellows. The tube 52 may preferably be contained within an outer coaxial shield tube 53, and enters the tank 20 at a point above the ordinary maximum level of the material therein. There the tube is secured to and communicates with the interior of a hollow metal bulb 54, here shown as contained in and supported by a guard cage 55 of heavy wire.

The bulb 54 is of thin walled but relatively rigid metal, preferably of a metal or metallic alloy, having relatively high heat conductivity and also not subject materially to corrosion by vapors from the material 21. In the case of acetone vapors for example, sheet copper will be a suitable material for the bulb. The walls of the bulb are wholly imperforate except for the sealed in tube 52 and except for a "breather" hole. This breather hole is not shown on the drawing because it is merely pinhole through the bulb wall at any convenient location, too small to be shown. It plays no part in the actual operation of the invention, merely acting to prevent false operation of the apparatus by normal slow changes of atmospheric temperature or barometric pressure, by allowing air to seep slowly into or out of the bulb and thereby keep the gas pressure within the bulb and bellows equal to the atmospheric pressure outside. However, this breather is too small to allow these

pressures to equalize in case a sudden rise of temperature about the bulb effects a rapid rise of pressure within it.

In such a case, before the breather hole can relieve the excess pressure within the bulb, this pressure transmitted through the pipe 52 will expand the bellows 51, drive the push rod 50 down on the lever arm 47 and lift the detent 45 from its engagement with the lever arm 43. The lever 41 will then rotate clockwise under the pull of the cord 40 and weight 39, allowing the weight 39 to turn the lever 38 to open the valve 36. The gas released by the valve passes through the connecting pipes and the nozzle 35 into the delivery trumpet 33, builds up sufficient pressure there to rupture the brittle diaphragm 31 and projects the fragments of this against the metal foil diaphragm 28 with sufficient force to rupture this. Inflammable gases or vapors, already presumably under some pressure from the abnormal heat in the vicinity of the bulb 54, are thus released and immediately so diluted with non-inflammable, smothering gas from the trumpet 33 that all danger of explosion or even of fire from these vapors is averted.

Ordinarily the parts of the chain of apparatus from the bulb 54 to the valve lever 38 are so proportioned that the system will operate at a temperature about the bulb 54 just a little lower than is required to expand the vapors in the tank 20 enough to rupture the diaphragm 28 themselves.

Although for convenience in drawing the gas tank 37 and the mechanism from the bellows 51 to the tank valve 36 are shown in close juxtaposition to the storage tank 20, these will in actual practice be located at some distance from the storage tank, as suggested by the breaks shown in the interconnecting pipe lines, perhaps even in another room. Then should external fire menace danger from the storage tank too imminent to permit of waiting for the automatic actuation, the cord 40 may be released from the lever arm 42 by means of the knot or handle 56 on the upper end of the cord. To this end the lever arm 42 is forked, the cord passes up through the fork, and the handle 56 rests on the legs of the fork. With the cord thus detached from the lever, the weight 39 is free to move the lever 38 to open the gas valve.

In the modified form disclosed in Figs. 2 and 3, the bulb 54 is replaced by a thermoelectric device 154 connected through wires 152 replacing the tube 52 to a solenoid 151 whose pull rod 150 actuates the lever arm 47.

Both of the arrangements above described operate upon the occurrence of an abnormally high temperature within the container 20. It may be that the pressure within the container could be raised to a dangerous value by other causes than heat. Thus the container might be used under conditions where accidental back pressures might occur. To meet the needs of such conditions the invention may be embodied in the modification disclosed in Fig. 4. Here the thermoelectrically responsive device 154 of Fig. 2 is replaced by a purely pressure responsive device such as a metallic bellows 254 which will shorten under external gas pressure and thus move the rod 257 to close an electrical switch 258 and thus actuate the solenoid of Fig. 3 upon the occurrence of an excessive pressure of predetermined amount within the container.

While all the forms above described are adapted to provide a blast of non-inflammable

gas or vapor from the nozzle 35, if desired the gas tank 37 could be replaced by a source of non-inflammable liquid, especially if the material 21 and its vapors are soluble or miscible in the particular liquid employed. The nozzle 35 would then be formed as the case might require, to deliver the liquid as foam, spray or in a jet according to its nature.

The embodiments shown are illustrative and may be modified and departed from in various ways without departing from the spirit and scope of the invention as pointed out in and limited only by the appended claims.

What is claimed is:

1. A safety apparatus for a container for materials which may evolve vapors and which container is provided with a relief aperture and means to close the same, the said apparatus comprising means to open the aperture and to surround the same with non-inflammable fluid, and means to actuate the last named means upon the occurrence of an abnormal condition within the container.

2. A safety apparatus for a container for materials which may evolve vapors and which container is provided with a relief aperture and means to close the same, the said apparatus comprising a nozzle opposed to the aperture and connected through a valve to a supply of non-inflammable fluid, and means actuatable by the occurrence in the container of an abnormal condition to open the valve to release fluid through the nozzle to open the aperture and to surround the same with the non-inflammable fluid.

3. A safety apparatus for a container for materials which may evolve vapors and which container is provided with a relief aperture and means to close the same, the said apparatus comprising a nozzle opposed to the aperture and connected through a valve to a supply of non-inflammable fluid, and temperature responsive means actuatable by the occurrence in the container of an abnormal temperature to open the valve to release fluid through the nozzle to open the aperture and to surround the same with the non-inflammable fluid.

4. A safety apparatus for a container for materials which may evolve vapors and which container is provided with a relief aperture and means to close the same, the said apparatus comprising a nozzle opposed to the aperture and connected through a valve to a supply of non-inflammable fluid, and pressure responsive means actuatable by the occurrence in the container of an abnormal pressure to open the valve to release fluid through the nozzle to open the aperture and to surround the same with fluid.

5. A safety apparatus for a container for materials which may evolve vapors and which container is provided with a relief aperture and a rupturable diaphragm to close the same, the said

apparatus comprising a nozzle opposed to the aperture and connected through a valve to a supply of non-inflammable fluid, and means actuatable by the occurrence in the container of an abnormal condition to open the valve to release fluid through the nozzle to rupture the diaphragm and to surround the aperture with fluid.

6. A safety apparatus for a container for materials which may evolve vapors and which container is provided with a relief aperture and a rupturable diaphragm to close the same, the said apparatus comprising a shatterable diaphragm spaced from and opposed to the rupturable diaphragm, a fluid ejection nozzle directed toward the shatterable diaphragm on the other side thereof from the rupturable diaphragm, means including a valve to supply non-inflammable fluid to the nozzle, and means actuatable by the occurrence in the container of an abnormal condition to open the valve to release fluid through the nozzle to shatter the shatterable diaphragm and project the fragments thereof to rupture the rupturable diaphragm while the fluid also surrounds the aperture.

7. A safety apparatus for a container for materials which may evolve vapors and which container is provided with a relief aperture and a rupturable diaphragm to close the same, the said apparatus comprising a shatterable diaphragm spaced from and opposed to the rupturable diaphragm, a fluid ejection nozzle directed toward the shatterable diaphragm on the other side thereof from the rupturable diaphragm, means including a valve to supply non-inflammable fluid to the nozzle, and temperature responsive means actuatable by the occurrence in the container of an abnormal temperature to open the valve to release fluid through the nozzle to shatter the shatterable diaphragm and project the fragments thereof to rupture the rupturable diaphragm while the fluid also surrounds the aperture.

8. A safety apparatus for a container for materials which may evolve vapors and which container is provided with a relief aperture and a rupturable diaphragm to close the same, the said apparatus comprising a shatterable diaphragm spaced from and opposed to the rupturable diaphragm, a fluid ejection nozzle directed toward the shatterable diaphragm on the other side thereof from the rupturable diaphragm, means including a valve to supply non-inflammable fluid to the nozzle, and pressure responsive means actuatable by the occurrence in the container of an abnormal pressure to open the valve to release fluid through the nozzle to shatter the shatterable diaphragm and project the fragments thereof to rupture the rupturable diaphragm while the fluid also surrounds the aperture.
